UNITED STATES PATENT OFFICE

HOWARD L. VINE, OF CANTON, OHIO, ASSIGNOR TO THE TIMKEN ROLLER BEARING COMPANY, OF CANTON, OHIO, A CORPORATION OF OHIO

GAUGING MACHINE

Application filed June 30, 1928. Serial No. 289,398.

This invention relates to gauging machines and has for its principal object to produce a gauging machine that will accurately determine the outside diameter and roundness and 5 concentricity of the outside and inside walls of annular articles of manufacture, such, for instance, as the circular cups or outer bearing members of roller bearings. Other objects are to provide a plurality of adjustments 10 whereby the gauging machine is adapted for gauging bearing cups of different diameters, to simplify the gauging operation, to provide means for accurately centering the cups on the machine, and to provide for simplicity 15 and cheapness of construction and compactness of design.

The invention consists in the gauging machine and in the construction, combinations and arrangements of parts hereinafter described and claimed.

In the accompanying drawings, which form part of this specification and wherein like symbols refer to like parts wherever they occur,

25 Fig. 1 is a front elevation of a gauging machine embodying my invention, parts of the machine being shown in vertical cross-section;

30 Fig. 2 is a horizontal cross-section through the machine on the line 2—2 in Fig. 1, the rotary work supporting table in plan view with cups of different diameters shown positioned thereon and indicated by means of dot-and-dash lines;

35 Fig. 3 is an enlarged horizontal cross-section on the line 3—3 in Fig. 1 through one of the supporting columns for the bearing supports for the gage arm supporting tube;

40 Fig. 4 is an enlarged vertical cross-section on the line 4—4 in Fig. 2 through one of the radial slideways in the work supporting table, showing the stop mounted therein;

45 Fig. 5 is a vertical longitudinal section through said slideway and stop on the line 5—5 of Fig. 4;

Fig. 6 is a vertical cross-section through the lower portion of the supporting arm for the outside indicating gage, said gage being 50 shown in front elevation;

Fig. 7 is a vertical section through the supporting tube for the arm which supports the outside indicating gage, the section being taken on the line 7—7 in Fig. 1;

Fig. 8 is a vertical section through the gage 55 arm supporting tube on the line 8—8 in Fig. 1, and looking in the direction of the inside indicating gage and the supporting arm therefor which are shown in elevation;

Fig. 9 is a front elevation of the lower 60 portion of the supporting arm for the inside indicating gage, showing said gage mounted in the adjustable slideway provided therefor on said arm;

Fig. 10 is a horizontal cross-section on the 65 line 10—10 in Fig. 9;

Fig. 11 is a side elevation of the cup centering device, showing the said device in position to center a cup on the rotary work supporting table;

Fig. 12 is a plan view of the centering device with parts thereof shown in section, and

Fig. 13 is a transverse cross-section through the centering device on the line 13—13 in 70 Fig. 11.

The present gauging machine is designed particularly for use in gauging annular cups or outer bearing members for roller bearings, although it is also adapted for gauging other annular articles of manufacture. The gauging machine comprises a circular work supporting table 1 provided at its center with a downwardly extending pilot 2 journaled in a bushing 3 provided therefor in the top of a suitable base or bed 4. The work supporting table is supported near its outer edge upon the conical rollers 5 of a taper roller bearing mounted on top of the bed beneath said table. For convenience in sliding large, heavy cups onto the rotary work supporting table plates 6 are secured to the top of the bed along the front edge thereof with their top surfaces flush with the top surface of said table.

Extending across the top of the circular work supporting table 1 along the diameter thereof is a horizontally disposed cross member, preferably in the form of a cylindrical tube T, which is supported at its ends for rotary and axial sliding movement in bear- 95 100

ings 7 provided therefor in bearing supports 8 sleeved on columns 9 fixed to outstanding brackets 10 provided therefor on opposite sides of the bed 4 of the machine. The bearing supports 8 are split and are provided with clamp screws 11 for clamping said sleeves to their supporting columns 9 in any desired position of their vertical sliding movement thereon. The cross tube T is provided at one end with a crank handle 12 for manually rotating it in its vertically adjustable bearing supports 8. Fixed to the top of each of the columns 8 is a gear box 13; and extending from the gear box on one column 15 to the gear box on the other column is a horizontal shaft 14 whose end portions extend through said gear boxes and are rotatably supported therein. Pinned on the shaft 14 within each gear box 13 is a beveled gear 15 which meshes with a similar gear 16 pinned on the upper end of a vertically disposed screw 17 that extends downwardly through said box alongside the supporting column 9 therefor and has its lower end portion threaded through a screw threaded opening provided therefor in a nut 18 bolted to the vertical face of the bearing support 8 mounted on said column. One end of the beveled gear shaft 14 is provided with a crank 19 for rotating it and the two screws 17 geared thereto to cause the bearing supports 8 to slide either upwardly or downwardly on the columns, depending on the direction in which the beveled gear shaft is rotated, and thus raise or lower 30 the cross tube T with respect to the work supporting table 1.

A gauge supporting member 20 has a split hub portion, which is sleeved on the cross tube T for rotary and axial sliding movement 40 thereon and is provided with clamping screws 21 for clamping said hub portion to said supporting tube, and a radially extending arm 22 provided at its free end with a split cylindrical bearing 23, which 45 extends longitudinally of said hub and is adapted to receive the horizontal shank 24 of a supporting body 25 for a suitable indicating gage 26, said shank portion being clamped in the split bearing of said arm by 50 means of suitable clamping screws 27. Slidably mounted in a longitudinal slideway 28 provided therefor in the shank 24 of the gage support 25 is a slide bar 29 provided at its work engaging end with a diamond 55 point 30 adapted to engage the outer periphery of the cup that is to be gaged and provided near its inner end with a shoulder 31 adapted to bear against a shoulder 32 formed adjacent to the pivot end of a lever 33 mounted 60 for vertical swinging movement in a recess located in said shank above said slide bar. The lever 33 is arranged so that its free end is adapted to bear against the lower end of the vertically slidable stem 34 of the indicating gage 26, whereby sliding movement

of the diamond carrying slide bar away from the center of the table 1 causes the free end of said lever to swing upwardly against the lower end of the stem of said indicating gage and thus actuate the pointer thereof. 70

The outer end of the horizontally slidable diamond carrying bar 29 carries a longitudinal pin 35 slideable in a bore provided therefor in an outstanding lug 36 or ear on the front face of the gage support 25 and is threaded at its outer end to receive knurled nuts 37 which abut against said lug and thus constitute an adjustable stop for limiting the sliding movement on said diamond carrying bar in the direction of the work. A coil 80 spring 38 is sleeved on the pin 35 between the opposing faces of the laterally projecting lug 36 and the outer end of the slide bar and operates to force the diamond carrying slide bar 29 in the direction of the work as far as the stop nuts 37 will permit.

Mounted on the cross tube T is a gage supporting arm 39 having a split hub portion, which is sleeved on said tube and is provided with a clamping screw 40 whereby it may be 90 clamped thereon in any desired position of adjustment, and a flat surface disposed in a plane parallel to the axis of the supporting tube and adapted to face the front of the machine. Swiveled to the flat front face of the gage supporting arm 39 by means of a flatheaded bolt 41 and a knurled nut 42 is a swivel plate 43 having a dovetail slideway 44 in its front face. A slide plate 45 has a dovetail rib 46 slideable in the dovetail slideway 44 in the swivel plate 43; and mounted on the front face of said slide plate adjacent to the lower end thereof is a suitable indicating gage 47 provided with a horizontally disposed axially movable stem portion 48, whose outer end is adapted to contact with the inner wall of the cup that is to be gauged and whose inner end is suitably connected with the gage mechanism (not shown) housed within the casing of the gage to operate the pointer 100 thereof.

The slidably and rotatably supported gage supporting plate 45 is prevented from sliding out of the slideway 44 in the swivel plate 43 by means of an outstanding pin 50 on one side of said gage supporting plate which pin abuts against an outstanding pin 51 located on the outer face of said swivel plate in the path of the pin carried by the slideable gage supporting plate. The dovetail rib 46 of the slide plate 45 is cut away intermediate its ends to form a transverse slideway 52, within which is located a friction slide 53 having a beveled end 54 adapted to bear against the adjacent undercut side of the dovetail slideway 44 in the swivel plate 43. The opposite end of said cross slide 53 is provided with a notch 55 within which is mounted a coil spring 56, one end of which bears against the flat face

- of a pin 57 carried by the slide plate 45, and the other end of which bears against the inner end of said notch and thus serves to force the beveled end 54 of said cross slide 53 into engagement with the adjacent undercut side of the dovetail slideway 44 in the swivel plate 43 to lock said slide plate in the said slideway in any position of its sliding movement therein. The friction slide 53 is released to permit sliding movement of the slide plate 45 in the dovetail slideway 44 in the swivel plate 43 by means of a lever 58. The lever is pivotally secured within a recess 59 in the slide plate for swinging movement in a plane parallel to the direction in which the spring-pressed cross slide travels. Said lever is arranged with one arm engaging a notch 60 provided therefor in the adjacent longitudinal edge of the cross slide 53; and the other arm of said lever is provided with an outstanding pin 61, which extends through an arcuate slot 62 provided therefor in the slide plate 45 and is located adjacent to a similar outstanding pin 63 fixed to the front face of the slide plate adjacent to the right hand end of said slot. With the arrangement just described, when it is desired to move the slide plate 45 along the slideway 44 in the swivel plate 43, the operator grasps the two pins 61 and 63 on the lever 58 and slide plate respectively and pulls the movable pin 61 towards the stationary pin 63, thereby causing the lever to swing on its pivot and thus disengage the spring-pressed cross slide 53 from the side wall of the slideway 44, thereby permitting free sliding movement of said slide along said slideway. When it is desired to change the angle of the slideway 44 in the swivel plate 43, the nut 42 on the bolt 41 is loosened and the swivel plate rotated on the supporting arm 39 about said bolt as a center by means of the pin 63, after which said nut may be tightened to again lock said swivel plate to said gage arm.
- 45 The cross tube is also provided with a contact carrying arm 64 having a split hub portion sleeved on said cross arm and adapted to be clamped thereon in the desired adjusted position by means of clamping screws 65. The contact carrying arm 64 is provided at its free end with a horizontal bore which extends parallel to the axis of the supporting tube and is threaded to receive a screw 66 having a knurled knob 67 at one end and a diamond point 68 at its other end, the contact screw being arranged with its diamond point nearest the center of the work supporting table in position to engage the outer periphery of the cup that is to be gaged. Sleeved on the rotary, axially slidable and vertically adjustable cross tube T, between right-hand bearing support 8 and the hub of the contact carrying arm 64, is a split collar 69 that is clamped to the tube in any desire position of its longitudinal movement thereon by means of a suitable clamping screw 70; and sleeved on said cross tube between said collar and said bearing support is a coil spring 71 which bears against said collar to shift said cross tube to the left and hold the contact point in engagement with the outer periphery of the cup. A split collar 72 is clamped on the left-hand end of the cross tube just inside the bearing support in position to abut against said support and thus prevent excessive travel of the tube due to the pressure of the spring 71.
- 70 The upper surface of the work table 1 is provided with two radially extending T-shaped slideways 73 spaced 90 degrees apart; and slidably mounted in each of said slideways is a stop member 74 having an upstanding portion provided at one end with a vertical face and at the other end with a beveled face which slopes downwardly and outwardly from the top of said stop to the T-shaped face portion thereof. The stops 74 are positioned on the work supporting table with their vertical end faces in position to engage the cup and are firmly clamped in the radial slideways in any position of their sliding movement therein by means of set screws 75 that are threaded through said stops and bear against the bottoms of said slideways.
- 75 The upper surface of the work table 1 is provided with two radially extending T-shaped slideways 73 spaced 90 degrees apart; and slidably mounted in each of said slideways is a stop member 74 having an upstanding portion provided at one end with a vertical face and at the other end with a beveled face which slopes downwardly and outwardly from the top of said stop to the T-shaped face portion thereof. The stops 74 are positioned on the work supporting table with their vertical end faces in position to engage the cup and are firmly clamped in the radial slideways in any position of their sliding movement therein by means of set screws 75 that are threaded through said stops and bear against the bottoms of said slideways.
- 80 The upper surface of the work table 1 is provided with two radially extending T-shaped slideways 73 spaced 90 degrees apart; and slidably mounted in each of said slideways is a stop member 74 having an upstanding portion provided at one end with a vertical face and at the other end with a beveled face which slopes downwardly and outwardly from the top of said stop to the T-shaped face portion thereof. The stops 74 are positioned on the work supporting table with their vertical end faces in position to engage the cup and are firmly clamped in the radial slideways in any position of their sliding movement therein by means of set screws 75 that are threaded through said stops and bear against the bottoms of said slideways.
- 85 The upper surface of the work table 1 is provided with two radially extending T-shaped slideways 73 spaced 90 degrees apart; and slidably mounted in each of said slideways is a stop member 74 having an upstanding portion provided at one end with a vertical face and at the other end with a beveled face which slopes downwardly and outwardly from the top of said stop to the T-shaped face portion thereof. The stops 74 are positioned on the work supporting table with their vertical end faces in position to engage the cup and are firmly clamped in the radial slideways in any position of their sliding movement therein by means of set screws 75 that are threaded through said stops and bear against the bottoms of said slideways.
- 90 The upper surface of the work table 1 is provided with two radially extending T-shaped slideways 73 spaced 90 degrees apart; and slidably mounted in each of said slideways is a stop member 74 having an upstanding portion provided at one end with a vertical face and at the other end with a beveled face which slopes downwardly and outwardly from the top of said stop to the T-shaped face portion thereof. The stops 74 are positioned on the work supporting table with their vertical end faces in position to engage the cup and are firmly clamped in the radial slideways in any position of their sliding movement therein by means of set screws 75 that are threaded through said stops and bear against the bottoms of said slideways.
- 95 The upper surface of the work table 1 is provided with two radially extending T-shaped slideways 73 spaced 90 degrees apart; and slidably mounted in each of said slideways is a stop member 74 having an upstanding portion provided at one end with a vertical face and at the other end with a beveled face which slopes downwardly and outwardly from the top of said stop to the T-shaped face portion thereof. The stops 74 are positioned on the work supporting table with their vertical end faces in position to engage the cup and are firmly clamped in the radial slideways in any position of their sliding movement therein by means of set screws 75 that are threaded through said stops and bear against the bottoms of said slideways.
- 100 The upper surface of the work table 1 is provided with two radially extending T-shaped slideways 73 spaced 90 degrees apart; and slidably mounted in each of said slideways is a stop member 74 having an upstanding portion provided at one end with a vertical face and at the other end with a beveled face which slopes downwardly and outwardly from the top of said stop to the T-shaped face portion thereof. The stops 74 are positioned on the work supporting table with their vertical end faces in position to engage the cup and are firmly clamped in the radial slideways in any position of their sliding movement therein by means of set screws 75 that are threaded through said stops and bear against the bottoms of said slideways.
- 105 The upper surface of the work table 1 is provided with two radially extending T-shaped slideways 73 spaced 90 degrees apart; and slidably mounted in each of said slideways is a stop member 74 having an upstanding portion provided at one end with a vertical face and at the other end with a beveled face which slopes downwardly and outwardly from the top of said stop to the T-shaped face portion thereof. The stops 74 are positioned on the work supporting table with their vertical end faces in position to engage the cup and are firmly clamped in the radial slideways in any position of their sliding movement therein by means of set screws 75 that are threaded through said stops and bear against the bottoms of said slideways.
- 110 The upper surface of the work table 1 is provided with two radially extending T-shaped slideways 73 spaced 90 degrees apart; and slidably mounted in each of said slideways is a stop member 74 having an upstanding portion provided at one end with a vertical face and at the other end with a beveled face which slopes downwardly and outwardly from the top of said stop to the T-shaped face portion thereof. The stops 74 are positioned on the work supporting table with their vertical end faces in position to engage the cup and are firmly clamped in the radial slideways in any position of their sliding movement therein by means of set screws 75 that are threaded through said stops and bear against the bottoms of said slideways.
- 115 The upper surface of the work table 1 is provided with two radially extending T-shaped slideways 73 spaced 90 degrees apart; and slidably mounted in each of said slideways is a stop member 74 having an upstanding portion provided at one end with a vertical face and at the other end with a beveled face which slopes downwardly and outwardly from the top of said stop to the T-shaped face portion thereof. The stops 74 are positioned on the work supporting table with their vertical end faces in position to engage the cup and are firmly clamped in the radial slideways in any position of their sliding movement therein by means of set screws 75 that are threaded through said stops and bear against the bottoms of said slideways.
- 120 The upper surface of the work table 1 is provided with two radially extending T-shaped slideways 73 spaced 90 degrees apart; and slidably mounted in each of said slideways is a stop member 74 having an upstanding portion provided at one end with a vertical face and at the other end with a beveled face which slopes downwardly and outwardly from the top of said stop to the T-shaped face portion thereof. The stops 74 are positioned on the work supporting table with their vertical end faces in position to engage the cup and are firmly clamped in the radial slideways in any position of their sliding movement therein by means of set screws 75 that are threaded through said stops and bear against the bottoms of said slideways.
- 125 The upper surface of the work table 1 is provided with two radially extending T-shaped slideways 73 spaced 90 degrees apart; and slidably mounted in each of said slideways is a stop member 74 having an upstanding portion provided at one end with a vertical face and at the other end with a beveled face which slopes downwardly and outwardly from the top of said stop to the T-shaped face portion thereof. The stops 74 are positioned on the work supporting table with their vertical end faces in position to engage the cup and are firmly clamped in the radial slideways in any position of their sliding movement therein by means of set screws 75 that are threaded through said stops and bear against the bottoms of said slideways.
- 130 The upper surface of the work table 1 is provided with two radially extending T-shaped slideways 73 spaced 90 degrees apart; and slidably mounted in each of said slideways is a stop member 74 having an upstanding portion provided at one end with a vertical face and at the other end with a beveled face which slopes downwardly and outwardly from the top of said stop to the T-shaped face portion thereof. The stops 74 are positioned on the work supporting table with their vertical end faces in position to engage the cup and are firmly clamped in the radial slideways in any position of their sliding movement therein by means of set screws 75 that are threaded through said stops and bear against the bottoms of said slideways.

tube 76 with a transverse bore adapted to receive a screw S upon which are rotatably supported two arms 90 disposed one on each side of said block. The opposing faces of the arms 90 and the block 84 are provided with cooperating ratchet teeth that are disposed radially with respect to the hubs of said arms and the bore in said block; and one end of the screw S is provided with a knurled head 91 that bears against the outer face of one of said arms, while the other end of said screw is threaded through the hub of the other of said arms, whereby tightening of said screw operates to clamp the arms to the sides of the block with the ratchet teeth of the arms and block in mesh, thereby firmly locking said arms to said block in the desired adjusted position. Located at the outer end of the centering device is a cup engaging finger frame comprising two parallel bars 92 that extend longitudinally of the telescoping members 76 and 77 on opposite sides of the longitudinal center line thereof and are connected at their outer ends by means of a cross rod 93. The outer ends of bars 92 terminate in depending fingers having convex surfaces adapted to rest on the upper end of the cup; and the inner ends of said bars are slidably supported in slideways provided therefor in the free ends of the two arms 90 located on opposite sides of the head 84 at the outer end of the tube 76. The slideways in the arms 90 extend parallel to the longitudinal axis of the telescoping members 76 and 77, whereby the work engaging bars are adapted to be adjusted longitudinally of said members and radially of the center of the table. The finger bars are adapted to be clamped to the supporting arms 90 in any desired adjusted position by means of knurled set screws 94 that are threaded through said arm and bear against the flat sides of said finger bars.

The gauging machine is used as follows: In gauging the outside diameter of a cup, the cup need not be accurately centered on the table; but may be placed on the table substantially in the position indicated by the dotted circle A shown in Fig. 2. The gage arm 39, which carries the inside indicating gage 47, is then swung out of the way by rotating said arm about one-quarter turn on the cross tube T and then clamping said arm thereto in such position. The cross tube T is then lowered by means of the crank 19 to bring the contact screw 66 on the arm 64 and the slide bar 29 of the indicating gage 26 opposite the outer periphery of the cup at diametrical opposite points. The collar 72 on the cross tube is then adjusted to cause the contact screw 66 to bear against the cup with some pressure and the cup to bear against the spring-pressed bar 29 of the indicating gage with somewhat less pressure. The outside diameter of the cup is then determined by slowly rotating the cross

tube T by means of the crank 12, to cause the contact members 29 and 66 to swing past the center of the cup, and the maximum reading of the gage 26 noted while so doing. A master cup of known diameter is used for setting the gage, and the maximum reading of the indicator during the gauging of the cup indicates whether the outside diameter of the cup is correct.

In gauging a cup for out-of-roundness or circularity and concentricity of inside and outside walls, the cup is accurately centered on the table, as shown at B by the dot-and-dash lines in Fig. 2, by means of the centering device illustrated in sheet 4 of the drawings. In centering the cup on the table the spherical socket 81 at one end of the centering device is engaged with the ball journal 82 provided therefor at the center of the table and the centering device adjusted in the manner hereinbefore described to bring the ends of the finger bars 92 to rest on top of the cup B and to bring the stem 87 of the indicating gauge into contact with the inner periphery of the cup. The centering device is then rotated within the cup about the axis of the table as a center and the cup shifted until no movement is imparted to the pointer of the gauge 86 during such rotary movement, thereby indicating that the cup is accurately centered on the table. The centering device is then removed, after which the adjustable stops 74 on the table are moved into engagement with the outer periphery of the cup and are locked to the table in this position.

In gauging the cup for concentricity of outside and inside walls, the diamond points of the indicating gages 26 and 47 are brought into engagement with the outer and inner walls, respectively, of the cup, in the manner hereinbefore described, and the table is then slowly rotated while the operator notes the reading of both gages. If the pointers of both gages remain stationary it indicates that the inner and outer peripheries of the cup are concentric; whereas, if one or the other of said pointers fluctuates it indicates the amount of eccentricity of the inner or outer periphery of the cup.

In testing the inside and outside walls of a cup for out-of-roundness, the cup is centered on the table in the manner above described and each wall is checked separately by using the gage 26 for checking the outside wall and the gage 47 for checking the inner wall while slowly rotating said table and carefully noting the reading of the gage engaged with the wall being checked, movement of the pointer indicating out-of-roundness and the amount thereof.

It is noted that the inside gage 47 is adapted to be adjusted for sliding movement at an oblique angle to the axis of the rotary work table by rotating the swivel plate 43 on the bolt 41, thereby adapting said gage for

use in gauging roller bearing cups having conical raceways.

In gauging the outside diameter of cups, the stops 74 are located outside of heavy cups 5 that are considerably higher than said stops and inside of the light weight cups that are lower than said stops. It is also preferable to locate said stops exteriorly of cups that are being gaged for inside circularity of out-of- 10 roundness. In practice it has been found that the weight of the larger cups is sufficient to hold them in place on the table after being centered thereon.

Obviously, the construction hereinbefore 15 described admits of considerable variation without departing from my invention.

What I claim is:

1. A machine for determining the diameter, 20 circularity and concentricity of the inside and outside walls of an annular article, said machine comprising a table for rotatably supporting said article, gauging devices located above said table in position to engage the inside and outside walls, respectively, 25 of said article at diametrically opposite points, a gauging device located above said table and adapted to engage the inside wall of said article, means whereby said gauging devices are adapted for independent 30 movement radially of said table, and means for raising and lowering said gauging devices with respect to said table.

2. A machine for determining the diameter, 35 circularity and concentricity of the inside and outside walls of an annular article, said machine comprising a table for rotatably supporting said article, gauging devices located above said table in position to engage the inside and outside walls, respectively, of 40 said article at diametrically opposite points, a gauging device located above said table and adapted to engage the inside wall of said article, means for raising and lowering said gauging devices simultaneously with respect 45 to said table, means whereby said gauging devices are adapted for independent movement radially of said table, and means whereby said gauging devices are adapted to swing in vertical planes at right angles to the direction 50 of their radial movement.

3. A gauging machine comprising a rotary work supporting table, gauging devices located above said work supporting table in position to engage the opposite sides 55 of work positioned thereon, a support for said gauging devices, said gauging devices being mounted for sliding movement towards and away from each other on said support along a diameter of said table, means for 60 raising and lowering said support with respect to said table, and means whereby one of said gauging devices is adapted to be raised and lowered independently of said support along an inclined plane disposed at 65 an oblique angle to the axis of said table.

4. A gauging machine comprising a rotary work supporting table, gauging devices located above said work supporting table in position to engage the opposite sides of work positioned thereon, a support for said gauging devices, said gauging devices being mounted for sliding movement towards and away from each other on said support radially of said table, means for raising and lowering said support with respect to said table, means whereby one of said gauging devices is adapted to be raised and lowered independently of said support along an inclined plane disposed at an oblique angle to the axis of the table, and means whereby the angle of such plane is adapted to be varied.

5. A gauging machine comprising a rotary work supporting table, gauging devices located above said work supporting table in position to engage the opposite sides of work positioned thereon, a support for said gauging devices, said gauging devices being mounted for sliding movement towards and away from each other on said support along a diameter of said table, means for raising and lowering said gauging members simultaneously, means whereby one of said gauging devices is adapted to be raised and lowered independently of said support along a plane disposed at an oblique angle to the axis of said table, means whereby the angle of such plane may be varied, and means for rotating said support upon a horizontal axis.

6. A gauging machine comprising a horizontally disposed work supporting table, a horizontally disposed cross member located above said table and extending from side to side thereof, columns located on opposite sides of said table and slidably and rotatably supporting said cross member, a gage arm rotatably and slidably mounted at one end on said cross member, a gauging device mounted on the free end of said gage arm and adapted to cooperate with the work supported on said table, and means for locking said gage arm to said cross member.

7. A gauging machine comprising a work supporting table, a cross member located above said table and extending from side to side thereof, columns located on opposite sides of said table, means slidably and rotatably supporting said cross member on said columns, gage arms slidably and rotatably mounted on said cross member, gauging devices carried by said gage arms and adapted to engage different surfaces of the work supported on said table, and means for locking said gage arms to said cross member in the desired adjusted position.

8. A gauging machine comprising a work supporting table, a horizontally disposed cross member located above said table and extending from side to side thereof, vertically movable supports for the ends of said cross member, mounting means on said machine

for said supports, means for simultaneously adjusting said supports on said mounting means, means for locking said supports in the desired adjusted position, gage arms slidably and rotatably mounted on said cross member, gauging devices mounted on said gage arms and adapted to engage work supported on said table, and means for locking said gage arms to said cross member in 10 desired adjusted position.

9. A machine for gauging annular articles comprising a horizontally rotatable table, gauging devices located above said table and adapted to cooperate with the inside and 15 outside diameters respectively of articles supported thereon, means whereby said gages are adapted for movement radially of said table, and means for swinging said gages in planes disposed at right angles to 20 the direction of their radial movement.

10. A machine for gauging annular articles comprising a horizontally rotatable table, gauging devices located above said table and adapted to cooperate with the articles supported thereon, means for raising and lowering said gages with respect to said table, means whereby said gages are adapted to be moved radially of said table, and means 25 for swinging said gages in a plane disposed 30 at right angles to the direction of their radial adjustment.

11. A gauging machine comprising a horizontally disposed rotatable work supporting table, a cross member located above said table 35 and extending from side to side thereof, columns located adjacent to the ends of said cross members, bearing members slidably mounted on said columns and rotatably supporting the ends of said cross member, gage 40 arms rotatably and slidably mounted at one end on said cross member, means for locking said gage arms to said cross member, and gauging devices mounted on the free ends 45 of said gage arms and adapted to engage the articles supported on said table.

12. A gauging machine comprising a circular horizontally disposed rotatable work supporting table, a cross member located above said table and extending from side to side thereof diametrically thereto, columns located adjacent to the ends of said cross member, bearing members slidably mounted on said columns and rotatably and slidably supporting the ends of said cross member, gage arms rotatably and slidably mounted at one end on said cross member, means for locking said gage arms to said cross member, means for urging said cross member in one direction of its sliding movement, gauging devices mounted on the free ends of said gage arms and adapted to engage the article supported on said table, and stops mounted on said table for radial sliding movement thereon.

13. A gauging machine comprising a hori-

zontally disposed rotatable work supporting table, a cross member located above said table and extending from side to side thereof, columns located adjacent to the ends of said cross members, bearing members slidably mounted on said columns and rotatably supporting the ends of said cross member, gage arms rotatably and slidably mounted at one end on said cross member, means for locking said gage arms to said cross member, gauging devices mounted on the free ends of said gage arms and adapted to engage the articles supported on said table, means mounted on said columns and engaging the slideable bearing supports thereon for simultaneously sliding said supports on said columns, and means for rotating said cross member in said bearing supports.

14. A gauging machine for gauging annular articles comprising a horizontally disposed rotary work supporting table, gauging devices located above said table and adapted to engage the outside wall of said article at diametrically opposite points, a gauging device located above said table and adapted to engage the inside wall of said article, a single vertically slideable and horizontally rotatable support for said gauging devices, means for raising and lowering said support, and means for rotating said support, said gauging devices being rotatably and slidably mounted at one end on said support.

15. A gauging machine for gauging annular articles comprising a horizontally disposed rotary work supporting table, said table having a center marker thereon adapted for cooperating with a device for centering the articles on said table, gauging devices located above said table and adapted to engage the outside wall of said article at diametrically opposite points, a gauging device located above said table and adapted to engage the inside wall of said article, a single support for said gauging devices, means for raising and lowering said support with respect to said table, said gauging devices being capable of rotary and longitudinal adjustment on said support and means whereby one of said gauging devices is adapted to be raised and lowered along a plane disposed at an oblique angle to the axis of said table.

16. In a machine for gauging annular articles, a rotary work supporting table having a center marker thereon, and means for centering the article on said table, said centering device comprising an extensible member having a portion adapted to rotatably engage the center marker of the table, a member adjustably mounted on said extensible member and adapted to engage the top of the article, and a gage mounted on said extensible member in position to engage the inner wall of the article being centered.

17. In a machine for gauging annular articles, a horizontally disposed rotary work

supporting table having a center marker thereon, and means for centering such articles on said table, said means comprising a telescopic member adapted to pivotally engage the marker at the center thereof, a work engaging member pivotally supported on said telescopic member and adapted to engage the top surface of the article being centered, and an indicating gage pivotally supported on said article engaging member in position to cooperate with the inner wall of said article.

Signed at Canton, Ohio, this 25 day of June 1928.

15 HOWARD L. VINE.
